UNITED STATES PATENT OFFICE

JOHN H. FOX, OF PITTSBURGH, PENNSYLVANIA, ASSIGNOR TO PITTSBURGH PLATE GLASS COMPANY, A CORPORATION OF PENNSYLVANIA

GLASS ROLLING APPARATUS

Application filed May 25, 1932. Serial No. 613,448.

The invention relates to glass rolling apparatus of the general type shown in the Gelsharp Patent No. 1,615,834, dated February 7, 1927, wherein a sheet of glass is rolled vertically from a molten bath by a pair of sizing rolls which engage the surface of the glass, such glass sheet after formation being directed horizontally through an annealing leer. The invention has for its principal objects the provision of improved means for supporting and driving the sizing rolls in a construction of the character specified. One embodiment of the invention is shown in the accompanying drawings, wherein:

15 Figure 1 is a side elevation partially in section. Fig. 2 is a sectional view, the right hand portion of which is taken on the line II—II of Fig. 1, and the left hand portion on the line IV—IV of Fig. 1. And Fig. 3 is an enlarged section similar to that of the right hand portion of Fig. 2.

Referring to the drawings, 1 is a draw pot or receptacle containing a bath 2 of molten glass which is supplied from a suitable melting tank, not shown, located to the right of the draw pot (Fig. 1). The glass is rolled from the pot by a pair of sizing rolls 3, 4 having their lower sides in engagement with the glass. These rolls are water cooled and driven as later described and the glass sheet 5 which is formed passes up over a series of apron rolls 6, 6, etc. (Fig. 1) and is then carried over other rolls into a roller leer, such leer construction being well known in the art. 35 The rolls each comprise a body portion 7 and a pair of spindles 8, 9 at the ends of the body portions. One of the spindles on each roll is connected with the driving mechanism and the driving mechanisms for the two rolls are 40 at opposite sides of the draw pot, as indicated in Fig. 2. Each of the roll spindles at the driven end of the roll is provided with a pair of swivels 10, 10 connected to the water inlets and outlet pipes 11, 12. A pipe 13 extends longitudinally of each roll and serves as the inlet for the water, the reverse flow going through the space 14 between the pipe and the interior of the roll.

45 The rolls and their driving mechanism are supported from above upon a framework 15

built up of commercial sections and mounted for vertical movement in order to adjust the position of the rolls with respect to the glass in the pot. The framework 15 is supported upon a fixed framework, including the vertical members 16 tied together by suitable cross members. The vertical adjustment of the framework 15 is accomplished by means of the screws 17 provided with worm wheels in the casings 18, these wheels being operated by worms on the shafts 19 provided with suitable operating cranks 20.

The sizing roll 3 and the apron rolls 6, 6, etc. are mounted in fixed position upon the framework 15 by means of depending arms 21 and the roll 4 is mounted for adjustment toward and from the roll 3 by reason of its mounting upon a pair of arms 22 pivoted to the arm 21 at 23. The upper ends of these arms are yieldingly pressed to the right (Fig. 1) by means of springs 24 whose tension is adjusted by the screws 25 working in the blocks 26 mounted in fixed position on top of the framework 15. The arms 21 and 22 are provided at their lower ends with the bearing bushings 27 provided with passages 28 therethrough, to which are connected the water inlet pipe 29 and the water outlet pipe 29a so that a circulation of water may be maintained through this bearing. This is 50 desirable because of the heat condition to which the bearing is exposed by reason of its proximity to the body of glass in the draw pot. Each roll is driven from a drive sleeve 30 which is journaled in an extension 31 of the arms 21 and 22. This sleeve is provided with a worm wheel 32 which is driven from a worm (Fig. 1) in the casing 33. This worm is carried by a stub-shaft whose upper end is connected by a universal joint with the 55 drive shaft 34. The drive shaft 34 is in turn driven from the shaft 35 through the intermediary of the bevel gearing 36, the shaft 37, the bevel gearing 38 the shaft 37a and bevel gears 38a (Fig. 1). The drive for each roll 60 is the same as will be seen by reference to Figs. 1 and 2 so that the foregoing description of the drive for the roll 3 will be a sufficient description for the drive of the other sizing roll 4. The drive sleeve 30 carries at its 65

left hand end (Fig. 3) a series of teeth which make engagement with teeth on a clutch member 39 secured to the spindle 8 so that the sizing roll is in this manner driven from the 5 drive sleeve 30. A clearance space is provided at 40 between the sleeve 30 and the spindle 8 of the roll. This arrangement permits of a satisfactory drive of the roll under the rather difficult conditions to which the apparatus is exposed. Due to the heat to which the rolls are exposed from the body of glass, they have a tendency to warp and since the rolls are supported in bearings 27 which are relatively fixed, and the outer ends of the 10 spindles 8 have a tendency to wobble and rotate out of true. The clearance space 40 permits of this wobbling action without binding and the clutch tooth engagement between the end of the sleeve 30 and the member 39 also permits this action without binding as there is sufficient clearance between the teeth to permit a relative rocking movement. The clutch member 39 has an additional function in that it is provided with a sprocket wheel 41 15 around which passes the sprocket chain 42 which drives one of the apron rolls 6, as indicated in Fig. 1. The other apron rolls are driven by suitable sprocket connections, one of which is the sprocket 43 shown in Fig. 1.

20 The advantages incident to the foregoing construction for supporting and driving the rolls will be apparent to those skilled in the art. It is desirable to have the rolls 3 and 4 of relatively small diameter in order to reduce their chilling effect upon the body of glass in the pot and under these conditions, the rolls have a tendency to sag, particularly in the production of a wide sheet. This is due to the weight of the rolls and to the pressure between the rolls due to the glass which tends to deflect them and, therefore, produce a sheet of unequal thickness. It is, therefore, desirable to get the supporting bearings for the rolls as close as possible together. This 25 is permissible with the construction heretofore described because of the use of the water cooled bearings which can be placed relatively close to the edge of the draw pot without injury to the bearings. The relatively loose driving connection between the roll spindles and the driving mechanism avoids any trouble as to binding which might otherwise occur due to the wobbling of the outer ends of the spindles as heretofore explained.

30 55 What I claim is:

1. In combination in vertical glass rolling apparatus including a pot or receptacle for carrying a bath of molten glass, and a pair of hollow horizontal sizing rolls disposed over the bath and each comprising a body portion with a spindle at each end, means for supporting the rolls comprising arms provided with bearings engaging the spindle adjacent the body portion of the roll, a driving sleeve journalled in one of said arms

outward of the bearing carried by said arm with a clearance space between the inner surface of the sleeve and the roll spindle, means for driving the sleeve, a clutch member secured to the spindle between the end of the sleeve and the bearing, and means on the end of the sleeve having driving connection with the clutch member permitting relative rocking motion between the clutch member and sleeve. 70

2. In combination in vertical glass rolling apparatus including a pot or receptacle for carrying a bath of molten glass, and a pair of hollow horizontal sizing rolls disposed over the bath and each comprising a body portion with a spindle at each end, means for supporting the rolls, comprising arms provided with bearings engaging the spindle adjacent the body portion of the roll, a driving sleeve journalled in one of said arms outward of the bearing carried by said arm with a clearance space between the inner surface of the sleeve and the roll spindle, means for driving the sleeve, a clutch member secured to the spindle between the end of the sleeve and the bearing, means on the end of the sleeve having driving connection with the clutch member permitting relative rocking motion between the clutch member and sleeve, and water connections swivelled 80 to the end of the spindle outward of said sleeve. 85

3. In combination in vertical glass rolling apparatus including a pot or receptacle for carrying a bath of molten glass, and a pair of hollow horizontal sizing rolls disposed over the bath and each comprising a body portion with a spindle at each end, means for supporting the rolls comprising arms provided with water cooled bearings engaging the spindle adjacent the body portion of the roll, a driving sleeve journalled in one of said arms outward of the bearing carried by said arm with a clearance space between the inner surface of the sleeve and the roll spindle, means for driving the sleeve, a clutch member secured to the spindle between the end of the sleeve and the bearing, and means on the end of the sleeve having driving connection with the clutch member permitting relative rocking motion between the clutch member and sleeve. 100

4. In combination in vertical glass rolling apparatus including a pot or receptacle for carrying a bath of molten glass, and a pair of hollow horizontal sizing rolls disposed over the bath and each comprising a body portion with a spindle at each end, means for supporting the rolls comprising arms provided with water cooled bearings engaging the spindle adjacent the body portion of the roll, a driving sleeve journalled in one of said arms outward of the bearing carried by said arm with a clearance space between the inner surface of the sleeve and the roll spindle, 110

means for driving the sleeve, a clutch member secured to the spindle between the end of the sleeve and the bearing, means on the end of the sleeve having driving connection with the clutch member permitting relative rocking movement between the clutch member and sleeve, and water connections swivelled to the end of the spindle outward of said sleeve.

10 In testimony whereof, I have hereunto subscribed my name this 16th day of May, 1932.

JOHN H. FOX.
